UNITED STATES PATENT OFFICE.

ALBERT PARTIN, OF TALKEETNA, TERRITORY OF ALASKA.

WRENCH.

1,425,415.

Specification of Letters Patent.

Patented Aug. 8, 1922.

Application filed November 12, 1918. Serial No. 262,180.

To all whom it may concern:

Be it known that I, ALBERT PARTIN, citizen of the United States, residing at Talkeetna, in the Third Division of the Territory of Alaska, have invented new and useful Improvements in Wrenches, of which the following is a specification.

This invention relates to wrenches, and the object is to provide a tool which shall be simple in construction and more efficient in operation than the similar tools ordinarily employed.

A further object is to provide a member comprising a movable jaw carrying a threaded shank, one portion of the shank being cut away longitudinally and the threaded portion thereof engaging a segmentally threaded portion of a sleeve for controlling the shank and jaw, the end of the sleeve 20 cooperating with the said jaw.

A still further object is to provide a construction of the character specified whereby a movable jaw is thrown to approximately the correct position, corresponding with the size of the nut to be operated upon, the movable jaw then being tightened by the rotation of the sleeve, the segmentally threaded portion of which engages the threaded shank subsequently to the movement of the jaw to the aforesaid approximate position.

With the foregoing and other objects in view, the invention consists in the novel construction, combination, and arrangement of elements hereinafter described and claimed.

In the drawings, Figure 1 is a view of the device in elevation, Figure 2 is a longitudinal section; Figures 3, 4 and 5 are 40 transverse sections on the lines 3-3, 4-4 and 5-5, respectively.

The movable jaw is designated 10, and includes a flat surface 11, and a notched surface 12 the latter cooperating with the 45 similarly notched surface 13 on the opposite jaw 14. The jaw last named includes a plain surface 15 cooperating with the plain surface of the jaw 10.

A shank 16 includes a flat side 17 extending longitudinally, the remainder of the surface of the shank from the point 18 to the point near the rear end of the shank being threaded. Jaw 14 is provided with a bore 20 having a flattened wall 21 engaged by the flat portion 17 of the shank

16. Jaw 14 is further provided with an annular portion 22 and an annular shoulder 23 having a curved surface.

A sleeve 25 is provided with a longitudinal bore 26 and with a segmental threaded portion 27 engaging the threads of the shank 16 when the sleeve is rotated to a position whereby the threads 27 pass from the flattened portion 17 to the shank. When the wrench is placed in position for engaging a nut or the like, the sleeve is in such position that threads 27 are opposite flattened side 17. This permits of the prompt movement of the shank and the jaw to approximately the correct position, at which time the sleeve is rotated causing engagement between threads 27 and the threads of the shank for effecting the accurate positioning of the jaw. A coil spring 30 surrounds the outer end of shank 16 and engages the end of sleeve 25, the outer end of the spring abutting the flange 31 on the shank, so that the sleeve will be normally spaced from the end of the shank by the spring and the jaws will be normally in contact. Pressure by the hand on the end portion of the shank will compress the spring and force jaw 10 to an outer position, and the removal of the hand will permit jaw 10 to approach jaw 14, engaging the nut or other object between the two jaws, after which the sleeve is rotated for producing engagement between threads 27 and the threads on the shank.

Sleeve 25 is provided with an inner annular channel 35 engaging an annular flange 23, and end portion 36 of the sleeve rests within annular channel 22 of jaw 14.

What is claimed is:

In a wrench, a shank provided with a threaded portion, one side of the shank being cut away at the threaded portion to form a plane surface, a jaw carried by one end of the shank, a second jaw provided with a bore through which the shank passes, the jaws having work-engaging portions on each side of the shank, providing independent tools for engaging round and flat surfaces, respectively, a sleeve having a bore receiving the shank and provided with a segmental threaded portion within the bore for engaging the threads of the shank, said sleeve also having an annular channel within one end of the bore, the channel having a curved wall, the second named jaw having a por- 110

tion of reduced diameter, and this jaw including an annular flange presenting a curved surface for engagement with the channel in the bore, the adjacent end of the 5 sleeve cooperating with the reduced portion, and a spring surrounding the shank beyond the sleeve and engaging the end of

the sleeve, for retaining the jaws in closed position when the threaded elements are disengaged.

In testimony whereof I affix my signature.

ALBERT PARTIN.
